Primary Examiner — Kelley A Donnelly(74) *Attorney, Agent, or Firm* — Intellectual Property Law Group LLP(57) **CLAIM**

The ornamental design for a tabletop vanity, as shown and described.

DESCRIPTION

FIG. 1 is a front perspective view of a tabletop vanity, embodying my new design;

FIG. 2 is a front view thereof;

FIG. 3 is a left side view thereof; the right side view being a mirror image thereof; and,

FIG. 4 is a top plan view thereof.

The broken lines are included for showing features that form no part of the claim.
